UNITED STATES PATENT OFFICE.

LINNAEUS C. POND, OF LOS ANGELES, CALIFORNIA, AND GEORGE C. WAGNER, OF DENVER, COLORADO.

INTERMITTENT GRIP DEVICE.

949,304.

Specification of Letters Patent. Patented Feb. 15, 1910.

Application filed April 15, 1907. Serial No. 368,451.

To all whom it may concern:

Be it known that we, LINNAEUS C. POND, of Los Angeles, California, and GEORGE C. WAGNER, of Denver, Colorado, both citizens 5 of the United States of America, have invented a new and useful Intermittent Grip Device, of which the following is a specification.

This invention relates to intermittent grip 10 devices and particularly to that type which employs a ball coating with a rotary and a gripping member for controlling the relative movement of the rotary member, and the main object of the present invention is 15 to provide a device of that character in which the rotary member has a free movement in either direction when moved quickly, but which is arrested and locked against movement in one direction upon being moved slowly.

The device as shown in the drawings is 20 particularly designed for use on shade rollers but it may be adapted to be employed in practically any mechanism in which an intermittent gripping or locking function is desired.

Referring to the drawings:—Figure 1 is 25 an end view of a shade roller, the end cap of the shade roller being in section. Fig. 2 is a sectional view of the end portion of a shade roller, the view being taken on line x^2-x^2 Fig. 1.

The invention comprises two members of 30 which the outer member has a revolute movement, with respect to the other; of one or more balls arranged intermediate said two members, the inner member being provided with a plurality of seats forming positive abutments for said balls, and the outer member being provided with one or more blind U-shaped radial pockets according to the 35 number of balls employed, each of said blind U-shaped radial pockets being sufficiently deep to receive the entire ball while fully 40 disengaged from the inner member, each radial pocket also having an offset recess, there being an abrupt shoulder formed between the main and offset recess whereby the main recess extends through an arc, which 45 arc embraces at least half of the circumference of the associated ball.

In the drawing 1 designates a hollow shade roller, at the end of which is an individual washer 2 which forms a bearing for

carrying the roller 1 on the relatively stationary axis 3.

4 designates the usual coil spring for imparting motion to the shade roller, one end of the spring being attached to the roller 1 and its other end being attached to the 50 shaft 3.

The end of the shaft 3 has the usual flattened end 5 which is received by the notch in the supporting bracket not shown. Formed on the shaft 3 is a flange 6 which 65 is provided with two inclined recesses or seats 7. A sheet metal cap 8 is fastened, preferably, by screws, to the end of the roller 1 and serves to house the operating parts of the device. Secured within the 70 cap 8 is a thick individual plate 9 of approximately cruciform shape and forming what may be termed the outer rotary member, which is provided with blind U-shaped radial pockets 10, either radial pocket being 75 large enough to completely receive a ball 11 and each radial pocket having a side recess 12. The pockets 10 extend entirely through the plate 9 which will permit of the plate being stamped out of sheet metal and 80 produced much cheaper and be less liable to breakage than if made from cast metal, as must be done where the pockets are formed as radial slots in the outer face of the disk or plate. The washer 2 can also be stamped 85 from thin sheet metal with a hole in its center only large enough for the passage of the axis 3, whereby the washer can be made very cheaply and forms one side of the pockets 10 while the cap 8 forms the 90 other side, when the parts are assembled.

The shade which is indicated in dotted lines in Fig. 1 is normally held checked against upward movement by a ball 11 acting as a block between a recess 12 and a 95 recess 7. One wall of each recess 7 is inclined as shown so that when the shade is pulled down in the direction of the arrow, Fig. 1, the ball is caused by the adjacent radial pocket 10 to ride up the incline fully 100 into the radial pocket. Then if the shade is allowed to rise quickly by the action of the spring, the rapid movement of the roller causes the balls to fly out and keep in the radial pockets so that clicking is avoided 105 and the movement is smooth and noiseless. By slowing this upward movement, a ball when it arrives at the top is allowed to drop

2 11
and seat itself between recess 12 and recess 7 which checks further upward movement of the curtain. Thus it will be seen that the engagement of the balls with the gripping member is controlled by centrifugal force, the balls being held out of engagement by centrifugal force when the rotary member has a swift movement, but engaging the gripping member when the movement of the rotary member does not produce the sufficient centrifugal force to throw out the balls.

What we claim is:—

The combination of a hollow roller, a relatively stationary shaft, an individual washer seating against the end of the roller and providing a bearing for the shaft, a coil spring having its ends secured respectively to the roller and to the shaft, a flange located on the shaft and having two oppo-

sitely disposed tangential recesses each formed with a rounded ball seat, an individual rotary plate of approximately cruciform shape extending across the roller having a central opening receiving the flange, and two oppositely arranged blind U-shaped radial pockets each formed with a rounded side recess, balls located in the radial pockets, and a cap confining the rotary oblong plate and balls against the washer. 25
